FISHHOOK AND TROTLINE HOLDER

Douglas Coalson, Brownwood, Tex.

Application November 7, 1938, Serial No. 239,325

10 Claims. (Cl. 43—31)

This invention relates to new and useful improvements in fishhook and trotline holders.

One object of the invention is to provide an improved holder for receiving and supporting the fishhooks attached to a trotline, whereby the hooks are completely enclosed so as to protect said hooks, as well as the person handling the same, from injury; the device also eliminating tangling of the line.

An important object of the invention is to provide a holder for receiving and supporting the fishhooks of a trotline, wherein the hooks are supported with their shanks in a substantially vertical position, with means for maintaining the same in such position, whereby the hooks cannot become entangled or pass each other within the holder and also whereby said hooks cannot be disengaged from the holder without removing them in the correct manner.

A particular object of the invention is to provide a holder of the character described, which is constructed so that the hooks cannot be inserted in or removed from the holder with their shanks at any angle except vertical, whereby insertion and removal of the hooks from the holder is simplified and made easy and "hanging up" of the hooks during such insertion and removal is obviated.

Another object of the invention is to provide a fishhook holder which consists of a hollow casing having one end open and also having a support therein on which the hook may be suspended, the holder also having a guide slot through which the stem or shank of the hook must slide, whereby the shank, as well as the hook is guided in its movement to make insertion of the hook easy and the removal thereof substantially automatic; the arrangement also preventing the hooks from becoming entangled or passing each other and also preventing removal of said hooks from any point other than the point of ingress.

A further object of the invention is to provide an improved holder of the character described, which may be constructed of a single piece of material, whereby manufacturing costs are materially reduced.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is an isometric view of a holder, constructed in accordance with the invention,

Figure 2 is an end elevation thereof,

Figure 3 is an end elevation showing the end opposite that illustrated in Figure 2,

Figure 4 is a view similar to Figure 2, showing a slightly modified form of the invention,

Figure 5 is a view similar to Figure 4 of still another form of the invention,

Figure 6 is a view similar to Figure 1 showing the casing cylindrical instead of angular,

Figure 7 is an end elevation of the holder shown in Figure 6,

Figure 8 is a view, similar to Figure 2, illustrating still another form of the invention, and

Figure 9 is an enlarged isometric view of the outer end of the first form of the invention.

In the drawing, the numeral 10 designates an elongate, hollow body or casing which is preferably constructed of light metal, although it may be of any suitable material.

In Figures 1 to 3, the casing is shown as substantially square in cross-section and is constructed of a single piece of metal. In forming the body, the material, of which said body is made, is bent upon itself to provide a vertical side wall A, top B, and side wall C. After forming the side wall C, the material is bent at substantially a right angle to provide a bottom D and this bottom terminates short of the opposite side wall A, as is clearly shown in Figures 1 and 2. The material is then bent upwardly to form a longitudinally, upright hook support 11, which extends throughout the length of the casing within the interior thereof.

This support may be inclined from the vertical toward the wall C or if desired, it could extend vertically. The extreme lower edge portion of the wall A is bent inwardly to form a longitudinal, inwardly extending flange 12. The flange lies in the same horizontal plane as the bottom D and the longitudinal edge of this flange is spaced from the support 11, whereby a longitudinal relatively narrow slot 13 is disposed in the bottom of the casing 10. Manifestly, the slot is contiguous or adjacent the upright hook support 11.

One end of the casing or body 10 is closed by an end wall 10', which wall may be integral with the body or may be a separate piece suitably secured thereto. The end wall abuts the edges of the side walls, top and bottom of the casing, as well as the edges of the support 11 and flange 12. The opposite end of the casing is open to permit insertion of the fishhooks, as will be explained, and the end portions of the support 11 and flange 12 are bevelled or cut away, as shown

at 14 to facilitate the insertion of said hooks into the casing (Figure 9). A suitable handle 15 is secured to the top B of the casing, whereby said casing may be readily carried.

As is well known, a trotline 16 has fishhooks 17 secured thereto at spaced points throughout the length thereof and difficulty has been experienced in handling such line without tangling the line and hooks carried thereby. By mounting the hooks within the casing 10, said hooks may be supported in their proper relation and danger of said hooks or line becoming entangled is obviated. Also the holder facilitates setting of said line.

In inserting a fishhook 17 within the holder, said hooks are moved inwardly through the open end of the casing 10, with the curved portion 17' of the hook engaging over the upper edge of the longitudinal support 11. This disposes the lower portion of the shank 11a in alignment with the longitudinal slot 13 in the bottom of the casing, whereby when the hook is moved inwardly of the casing the shank enters said slot. In this manner, the curved portion of the hook is riding or sliding along the top of the support 11, whereby it is guided therealong, while the shank of said hook is guided by the slot 13. Thus, the hook is maintained in substantially an upright position and its movement along the support is made easy, whereby "hanging up" of said hook, due to its turning within the support, is impossible.

The slot 13 is relatively narrow being only sufficiently wide to permit free movement of the hook shanks therethrough. It is not wide enough to allow the shank of one hook to pass another and thus each hook is maintained in its proper position with relation to the other hooks on the line. This prevents the hooks from becoming tangled with each other and thereby eliminates tangling of the line 16. Since the hooks 17 are positively guided at their shanks as well as at their curved portions, movement of the hooks along the support is smooth and it has been found that the hooks may be inserted or removed by merely tilting the casing, which make the action substantially automatic.

It is not essential that the hook support 11 be inclined from the vertical and in Figure 4, said support is shown as extending substantially vertically within the casing. When extended vertically, it is desirable that the support be spaced inwardly of the slot 13 and for this purpose an offset 11' is formed at the base of the support. By offsetting the support, the upper edge of said support is sufficiently spaced from the wall A to accommodate the curved portion 17' of the hook 17. Obviously, the hooks are inserted and removed in the same manner as described.

Although it is desirable that the support 11 be integral with the casing 10, it could be made separate therefrom. In such event, the support 11a, as shown in Figure 5, has its lower edge position soldered, or otherwise secured, to the bottom of said casing.

In Figures 6 and 7, the casing is shown as tubular in cross-section, being constructed in the same manner as the form shown in Figure 1. The upper edge portion of the support 11 is illustrated as bent inwardly at substantially a right angle to provide a flange 11b on which the curved portion of the hook 17 may slide. This flange may, if desired, be provided on the supports of the other modifications disclosed in Figures 1 to 5. It may be desirable in some instances to provide a double support within the

casing and such construction is shown in Figure 8. The casing is constructed in substantially the same manner as the form shown in Figure 1, with the exception that the slot 13' is located centrally of the bottom of said casing. Instead of the single support 11, a pair of supports 11c extend upwardly on each side of the slot and as illustrated, said supports are integral with the bottom, although they may be separate members suitably fastened in position. In this modification, it is manifest that the shank of the hook is guided through the slot 13' and the hook or curved portion may be engaged over either one of the supports.

In all forms, the hooks are guided at their curved portions 17', as well as the shanks 11a thereof, whereby their movement through the casing is facilitated. It is noted that although the slot in the bottom of the casing is shown intermediate the side walls, it may be located immediately adjacent said side wall, provided that the shape of the hook is such as to permit its insertion and removal in the manner described.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent, is:

1. A trotline holder including, a casing having one end open, a pair of upright supports spaced from each other within the casing, each support being arranged to receive the curved portion of a fishhook whereby said hook is suspended from the support, and means for confining and guiding the shank of the hook when so suspended.

2. A trotline holder including, an elongate casing having a longitudinal slot in the bottom, a longitudinal hook support within the casing adjacent the slot, whereby said slot accommodates the shank of a hook when the same is suspended from the support, and an arcuate flange on which the curved portion of a hook may slide formed on the upper edge portion of said support.

3. A trotline holder including, an elongate casing having a longitudinal slot in its bottom, and a longitudinal hook support within the casing adjacent the slot, whereby said slot accommodates the shank of a hook when the same is suspended from the support, the outer end portions of said support and of the casing adjacent the slot being beveled to facilitate the insertion of a hook into said slot and casing.

4. A trotline holder including, an elongate casing having a longitudinal slot in its bottom, and a longitudinal hook support within the casing having its lower end adjacent the slot, the support being disposed in a plane at an acute angle to the bottom of the casing and being inclined away from and to one side of the vertical plane in which said slot is disposed, the slot accommodating the shank of a hook when the same is suspended from the support.

5. A trotline holder including, an elongate casing having a longitudinal slot in its bottom, a longitudinal hook support within the casing having its lower end adjacent the slot, the support being disposed in a plane at an acute angle to the bottom of the casing and being inclined away from and to one side of the vertical plane in which said slot is disposed, one end of the casing being open, whereby fishhooks may be inserted within said casing, each hook having

its curved portion engaging over and slidable along the support with its shank extending through the slot, whereby the hooks are positively guided in their longitudinal movement within the casing, the slot being of such width that the shanks of adjacent hooks cannot pass each other within said slot, thereby preventing the hooks from becoming entangled with each other.

6. A trotline holder including, an elongate casing having a longitudinal slot in its bottom, and a longitudinal hook support within the casing having its lower end adjacent the slot, the support being disposed in a plane at an acute angle to the bottom of the casing and being inclined away from and to one side of the vertical plane in which said slot is disposed, the slot accommodating the shanks of hooks suspended from the support and being of such width that the shanks of adjacent hooks cannot pass each other within said slot, thereby preventing said hooks from becoming entangled with each other.

7. A trotline holder including, an elongate casing having a longitudinal slot in its bottom portion, and a longitudinal hook support within the casing having its lower end adjacent the slot, the support being inclined to one side of the slot, whereby the upper edge portion of said support lies outside of the vertical plane in which said slot is disposed, the support being arranged to receive the curved portion of a fishhook, whereby the hook is suspended from said support in a substantially upright position and the barb and point of the hook are spaced away from the support.

8. A trotline holder including, an elongate casing having a longitudinal slot in its bottom portion, and a longitudinal hook support within the casing having its lower end adjacent the slot, said slot accommodating the shank of a hook when the same is suspended from the support, said support being disposed in a plane at an acute angle to the bottom portion of the casing, the plane of the support being inclined away from a vertical plane passing through the slot so that the barb and point of the hook will be held away from said support.

9. A trotline holder including, an elongate casing having a longitudinal slot in its bottom, a longitudinal hook support within the casing having its lower end adjacent the slot, the support being disposed in a plane at an acute angle to the bottom of the casing and being inclined away from and to one side of the vertical plane in which said slot is disposed, and an arcuate flange on which the curved portion of a hook may slide provided on the upper edge portion of said support.

10. A trotline holder including, an elongate casing having a longitudinal slot in its bottom, a longitudinal hook support within the casing having its lower end adjacent the slot, the support being disposed in a plane at an acute angle to the bottom of the casing and being inclined away from and to one side of the vertical plane in which said slot is disposed, the outer end portions of said support and of the casing adjacent the slot being bevelled to facilitate the insertion of a hook into said slot and casing.
